INSULATING BUSHING

William H. Jacobi, Wilkinsburg, Pa., assignor to
Westinghouse Electric & Manufacturing Company, East Pittsburgh, Pa., a corporation of Pennsylvania

Application April 11, 1941, Serial No. 388,089

3 Claims.

(Cl. 174—19)

The present invention relates to bushings for insulating the conducting leads of high tension electrical apparatus such as transformers and circuit breakers and it has particular relation to an improved means for sealing the interior of such a bushing from the outside air and moisture.

Bushings of this type generally comprise an elongated tubular casing of insulating material such as porcelain, through which the conductor or lead from the apparatus extends to be connected at the upper end of the casing to an outside terminal. This terminal is in turn adapted to be connected to an electric supply circuit. By reason of the difference in the temperature coefficients of expansion of the insulating casing and the metallic conductor, it is difficult to maintain the bushing fluid-tight and to prevent breathing of the outside atmosphere upon changes in temperature. The bushings are usually filled with a dielectric fluid, such as a gum or oil, from which all impurities must be excluded.

With the prior art methods of sealing the inside of the bushing, the insulating casing is generally compressed between parts fixed to the metallic conductor and as a result may be subjected to severe stresses upon changes of temperature. According to the present invention, however, a weatherproof seal is provided without subjecting the insulating casing to such dangerous stresses. This is accomplished by providing a resilient sleeve member between the conductor and the opening in the insulating casing. This sleeve is adapted to close the space between these two members irrespective of relative longitudinal movement therebetween and will provide a satisfactory seal without exerting any particular force on the casing. It is within the scope of the invention to vulcanize or cement this resilient sleeve to either one or both of the members which it contacts in order to maintain it in place. This latter result may also be accomplished by means of collar members secured to the conductor in lieu of vulcanizing or cementing.

It is accordingly an object of the present invention to provide a bushing construction which is comparatively simple and which provides a complete weatherproof seal without causing any dangerous stresses to be exerted upon the insulating casing.

It is another object of the invention to provide an insulating bushing in which a resilient sleeve is disposed between the conductor and the end

of the bushing to furnish a moisture-proof seal therebetween.

A further object of the invention is to provide an insulating bushing, the ends and other openings of which are effectively sealed by means of resilient sleeve members.

Other objects and advantages of the invention will appear from the following detailed description read in conjunction with the accompanying drawing in which:

Fig. 1 is a view in elevation, with parts broken away, of a bushing assembly in accordance with the present invention.

Fig. 2 is an enlarged vertical view, with parts in section and parts broken away, of the apparatus of Fig. 1.

Fig. 3 is an enlarged sectional view of the removable plug shown in Fig. 2, and

Fig. 4 is a view similar to Fig. 2 of a portion of a modification of the invention.

Referring to Fig. 1 of the drawing, the bushing may comprise a tubular casing 2 of dielectric material, such as porcelain, having a plurality of surface creepage flanges 4 of a usual construction. The casing 2 rests upon a metallic sleeve 6 which supports a metallic clamping flange 8. The flange 8 is secured to the casing 10 of an electric transformer or similar apparatus by means of bolts 12.

By way of example, the present invention may be used with a bushing of the condenser type in which elongated layers of conducting and insulating material are wound around a rigid metallic conductor. In the drawing, the condenser wrapping which is designated as 14 is applied to a terminal stud or conductor 16. The central portion of this condenser is disposed within the metallic collar or sleeve 6 which may be applied thereto in any suitable manner such as that shown in Patent No. 2,088,502, issued July 27, 1937, to E. E. Arnold et al. It is intended that the condenser wrapping fit tightly within the collar so that an oil-tight joint is obtained therebetween to prevent leakage of insulating fluid.

Referring to Fig. 2, it will be seen that the lower end of the tubular casing 4 is provided with an opening indicated at 18. This opening is nearly cylindrical but preferably tapers slightly to an increased diameter at its outer end. The conductor and condenser structure is disposed within the bushing in such a manner that the metallic sleeve 6 fits within the opening 18 and a resilient sleeve member 20 is disposed within the annular space therebetween to close the bottom of the bushing about the metallic sleeve. It is

preferred to provide the taper in the opening 18 in order to facilitate insertion of this sleeve into its position and to vulcanize or cement the sleeve to the surface of the opening 18 as indicated at 19.

This opening will generally be machined to size and the irregularities which result on its surface from this operation will promote firm engagement between the casing and the sleeve. This rough character of the surface 19 will likewise improve the frictional engagement between the parts when the vulcanizing or cementing is dispensed with.

A metallic collar member 22 is secured to the metallic sleeve 6 adjacent the inner end of the resilient sleeve 20 by any suitable means such as soldering. In addition, a portion of the flange 6 is screw-threaded as indicated at 24 so as to be engaged by a cap or nut member 26. This nut member 26 is in turn provided with an annular upwardly extending projection 28 which is adapted to engage the lower surface of a clamping ring or gasket 30. This clamping ring 30 is preferably of metal and is of such a thickness that it may be moved freely within the angular space between the casing opening 18 and the flange member 6 in order to compress the resilient sleeve 20 against these two surfaces.

The upper end of the casing 2 is likewise provided with a slightly tapering cylindrical hole 32 through which the conductor 16 extends. The casing preferably extends inwardly at this end to assume a dome-shape and provide sufficient space within the bushing for expansion of the insulating fluid. The surface of the opening 32 is preferably left in a roughened condition for the same reasons set forth above.

A resilient sleeve 34 is disposed within the opening 32 to seal the space between the casing and the conductor and may be vulcanized or cemented to the opening at 33 if desired. A second metallic collar member 36 is secured to the conductor to engage the lower end of this sleeve while a cap 38 is secured to a threaded portion 40 of the conductor. This cap includes an annular flange 41 which extends beyond the top edge of casing 2 and has a downwardly extending annular portion 42. This portion 42 is adapted to engage a clamping ring 44 to cause it to compress the resilient sleeve 34. Likewise a resilient gasket member 46 is disposed between the bottom of the cap 38 and the top of the casing 2 to prevent moisture from entering the opening.

A fish paper gasket 48 is cemented on the upper edge of the cap 38 and closely engages the threaded portion 40 of the conductor 16 to prevent any moisture entering the opening through the threads. A lock nut 50 is threaded to the portion 40 of the conductor to maintain the device in assembled position and furnish a base against which an electrical conductor may be secured for connection with the apparatus within the casing.

It will appear that the resilient sleeves 20 and 34 will be compressed between their cooperating collars so as to completely seal the openings in which they are disposed. These collars, in addition, will prevent displacement of the sleeves even when they are not cemented to the opening, and it is within the scope of the invention to so dispense with the cementing or vulcanizing operation.

At the lower end of the bushing is an opening 52 for filling and draining the device of insulating fluid. This opening is adapted to be closed

by means of a removable plug 54 which is shown more in detail in Fig. 3 of the drawing. As shown in this figure, a resilient sleeve 56 is disposed within the opening while a bolt designated as 58 and having a conical portion 60 at its inner end in turn extends through the sleeve. The bolt 58 includes a head 62 which is larger than the inner diameter of the sleeve 56 yet smaller in diameter than the opening 52. Disposed between the inner surface of the sleeve 56 and the bolt 58 is a split metallic sleeve designated at 64 which has a first conical surface 65 for engaging the surface of the bolt at 60 and a second conical surface 66 adapted to be engaged by an annular wedge 68 of triangular cross-section. This wedge 68 is movable axially along the bolt when a nut 70 is tightened thereon to extend the sleeve 64 and compress the resilient sleeve 56 against the roughened surface of the opening 52. The bolt 58 may be slotted at its outer end as shown at 71 to facilitate holding it in place while tightening the nut 70. A lock nut 72 may be provided, if desired.

It will be evident that upon loosening the nut 70, the resilient sleeve 56 will come back to its original position, so that the entire plug assembly may be removed from the opening to permit filling or draining the interior of the bushing. When in this condition, the plug assembly may likewise be reinserted in the opening. Upon again tightening the nut 70 on the bolt, the plug is extended to its largest size to completely seal the opening.

While in Fig. 2 the resilient sleeves 20 and 34 may be maintained in position between the casing and conductor by means of the longitudinal forces exerted thereon by the collars and caps, it is also within the scope of the invention to dispense with these collars. In Fig. 4 is shown such a modification in which cementing, vulcanizing or the like is relied upon entirely for maintaining the resilient sleeves in place. As shown in this figure, a resilient sleeve 34' is secured to the conductor 16' as by cementing or vulcanizing at 74. The sleeve 34', in addition, engages a surface of the opening 32' at the end of the casing 2' and may be cemented thereto as shown at 76. A cap member 38' is secured to the threaded portion 40' of the conductor so as to compress a resilient gasket 46' between its lower surface and the upper end of the casing. A gasket 48' and lock nut 50' may be employed in a manner similar to the arrangement of Fig. 2.

The lower end of the casing of the apparatus of Fig. 4 may be assembled in this same manner and the collar shown at 22 in Fig. 2 dispensed with.

From the foregoing it will appear that the present invention provides a novel and improved means for sealing the interior of an insulating bushing in such manner that the casing is not subjected to any dangerous stresses as a result of longitudinal movement between it and the conductor assembly. As the resilient sleeve itself is protected from moisture, these sealing properties will be maintained over a long period of time.

Since various modifications of the specific apparatus shown and described will appear to those skilled in the art, it is intended that the invention should be limited only by the appended claims interpreted in view of the prior art.

I claim as my invention:

1. In an insulating bushing, a tubular insulating casing defining an insulating chamber, and having an end portion extending inwardly to form a substantially circular opening, a rigid conduc-

tor extending axially through said casing, a resilient sleeve disposed in said opening about said conductor and compressed therebetween, means for securing said resilient sleeve in said position to provide a sealing joint despite relative longitudinal movement between said casing and said conductor, a resilient gasket disposed about said conductor on the outside of said end of said casing, and a cap member secured about said conductor to compress said gasket against said casing.

2. In a high tension insulating bushing, a tubular insulating casing defining an insulating chamber and having an end portion extending inwardly to form a substantially circular central opening, a rigid conductor extending axially through said casing, a resilient sleeve disposed in said opening about said conductor and compressed between it and the edge of said opening to form a seal therebetween, a resilient gasket engaging the outside of said casing about said opening, a collar member secured to said conductor to engage the inner end of said sleeve and limit its inward movement, a cap secured to the

end of said conductor to compress said gasket against said casing, and an annular projection on said cap for fitting within the space between said conductor and said casing to engage the outer end of said sleeve.

- 5 3. In a high tension insulating bushing, a tubular insulating casing defining a central insulating chamber and having an end portion extending inwardly toward the axis thereof to form an axial opening, a rigid conductor extending axially through said casing, a resilient sleeve disposed in said opening about said conductor, a resilient gasket engaging the outside of said casing about said opening, a collar member secured to said conductor to engage the inner end of said sleeve and limit its inward movement, a cap secured to the end of said conductor to compress said gasket against said casing, and an annular member forced against the outer end of said sleeve by said cap to compress the sleeve into sealing engagement with said casing and said conductor.

WILLIAM H. JACOBI.
